UNITED STATES PATENT OFFICE.

THOMAS JAMES LITTLE, JR., OF WOODBURY, NEW JERSEY, ASSIGNOR TO WELSBAUGH COMPANY, OF GLOUCESTER CITY, NEW JERSEY, A CORPORATION OF NEW JERSEY.

GLOBE-HOLDER FOR LAMPS.

1,008,836.

Specification of Letters Patent. Patented Nov. 14, 1911.

Application filed June 12, 1911. Serial No. 632,566.

To all whom it may concern:

Be it known that I, THOMAS J. LITTLE, Jr., of Woodbury, Gloucester county, New Jersey, have invented a new and useful 5 Globe-Holder for Lamps, of which the following is a full, clear, and exact description, reference being had to the accompanying drawings, forming part of this specification, in which—

10 Figure 1 is a side view, partly broken away, showing my invention applied to a lamp and globe; Fig. 2 is a sectional plan view, also partly broken away; and Fig. 3 is a perspective view of the holding ring re- 15 moved.

20 My invention has relation to globe holders for lamps, and more particularly to that class of globe holders which employ a spring clamping or holding ring for the neck of 25 the globe.

My invention is designed to provide a spring ring of this character having a novel and effective means for centering the globe and preventing the weight of the globe from 30 sagging the ring.

35 The nature of my invention will be best understood by reference to the accompanying drawings, in which I have shown the preferred embodiment thereof, and which 30 will now be described, it being premised, however, that various changes may be made in the details of construction and arrangement of the parts without departing from the spirit and scope of my invention as defined in the appended claims.

In the drawings, the numeral 2 designates a lamp casing having a depending gallery portion 3, within which the neck 4 of the globe 5 is arranged to be received and held.

40 In the drawings, I have shown my invention as applied to a globe having a metal neck, but it will be understood that my invention is equally applicable to glass globes having integral glass necks.

45 6 is the spring holding ring, which is preferably formed from a single piece of wire bent to form a complete holding circle, with its ends overlapping and extending partially around this circle at each side, 50 these free ends terminating in the bends 7 which bear against the inner side of the gallery flange in the groove 8 provided therefor. The ring is formed with the central guide bend or loop 9, which extends 55 through a slot 10 in the gallery flange, and

each of the overlapping end portions has the outward loop or bend 11. These loops or bends 11 extend outwardly through the elongated slots 12 in the gallery flange, said slots being at slightly different levels, as shown in Fig. 1. The end portions of the ring adjacent to each of the bends or loops 11 is formed with an inward cam bend 13, one of these bends projecting underneath the clamping portion of the ring, while the other bend projects above said clamping portion. These cam bends 13 engage the neck of the globe, and serve to largely take the weight thereof so as to prevent the clamping portion of the ring from sagging. 70 One of the bends being extended underneath the clamping portion of the ring also assists in supporting it. These bends 13 also serve to center the globe.

75 It will be readily seen that when the two loops or bends 11 are pressed toward each other by the fingers, the effect is to expand the holding portion of the ring so that the neck portion of the globe can be inserted or withdrawn therethrough, the cam bends 13 receding sufficiently to clear the neck. As soon as the bends 11 are released by the fingers, the spring action of the ring causes it to contract into clamping engagement with the neck of the globe. 80

85 The advantages of my invention result mainly from the provision of the inward cam bends 13 whereby the globe is centered and its weight is prevented from sagging the ring, thus enabling the latter to be made 90 of relatively light wire.

95 What I claim is:

1. In a globe holder, an expandable and contractible globe-holding ring having overlapping ends an inward bend or projection on each end adapted to engage the neck of the globe to center the globe, and also to prevent the weight of the globe from sagging the ring; substantially as described.

100 2. A globe-holding device for lamps, comprising a holding ring formed of a single piece of wire bent into approximately circular form, with overlapping ends, and having projecting guide loops, and also having an inward bend or projection on each end 105 adapted to engage the neck of the globe; substantially as described.

110 3. A globe-holding device for lamps, comprising a holding ring formed of a single piece of wire bent into approximately circu-

lar form, with overlapping ends, and having projecting guide loops, and also having an inward bend or projection on each end adapted to engage the neck of the globe, one 5 of said projections extending underneath the clamping portion of the ring; substantially as described.

4. In a globe holder, an expansible and contractible globe-holding ring having overlapping ends, an inward bend or projection on each end adapted to engage the neck of 10

the globe to center the globe, and an outwardly extending bend at each end of the overlapping portion arranged to seat in the inner side of the gallery, substantially as 15 described.

In testimony whereof, I have hereunto set my hand.

THOMAS JAMES LITTLE, JR.
